CLAIM

The ornamental design for a work vehicle cab, as shown and described.

DESCRIPTION

FIG. 1 is an elevated perspective view as seen from the left front of the work vehicle cab embodying our design; FIG. 2 is a front elevation view of the work vehicle cab; FIG. 3 is a left side elevation view of the work vehicle cab; FIG. 4 is a rear elevation view of the work vehicle cab; FIG. 5 is a top elevation view of the work vehicle cab; and, FIG. 6 is a bottom elevation view of the work vehicle cab. The broken lines shown throughout the drawing are for illustrative purposes only and form no part of the claimed design.
